UNITED STATES PATENT OFFICE.

CHARLES HAVLISH, OF ELKHART, INDIANA.

PUNCH-PRESS GUARD.

Application filed October 8, 1921. Serial No. 506,344.

To all whom it may concern:

Be it known that I, CHARLES HAVLISH, a citizen of the United States, residing in the city of Elkhart, county of Elkhart, Indiana, have invented certain new and useful Improvements in Punch-Press Guards, of which the following is a specification.

The invention relates to safety means for machines having a reciprocating part which 10 coacts with a stationary part to produce articles by punching, stamping, or the like.

It is an object of the invention to provide a guard adapted to screen the space between the reciprocating part and the stationary part upon reciprocation so as to prevent injury to the hands of a careless operator.

It is a further object of the invention to provide improved means for arranging the guard in functional position during operation of the machine.

It is another object of the invention to provide cam-operated means to dispose the guard in functional position.

It is also an object of the invention to provide a guard which may be secured to machines which are already built and may be secured thereon with little inconvenience.

It is a further object of the invention to 30 provide a casing for the cam-actuated means, which casing may be secured to machines which are already built.

It is furthermore an object of the invention to provide certain features of construction and arrangement whereby devices of this particular type are enhanced in utility and improved in function.

With these and other objects in view, which will appear as the description of the 40 invention proceeds, the latter comprises the means set forth in the following specification, particularly pointed out in the claims forming a part thereof, and illustrated in the accompanying drawings, in which:

Fig. 1 is a fragmentary front elevation of 45 a press to which the invention has been applied.

Fig. 2 is a fragmentary side elevation showing the arrangement of the guard and 50 associated parts.

Fig. 3 is a fragmentary front elevation in which the guard is in inoperative position to permit access to the space between the reciprocating and stationary parts of 55 the press.

Fig. 4 is a top plan view of the casing

containing the cam-operated means for actuating the guard.

Fig. 5 is a sectional elevation of the casing.

Fig. 6 is an end elevation of the casing, 60 with the cover removed.

Fig. 7 is a sectional elevation, similar to Fig. 5, with the parts in a different position.

Referring to the several figures of the drawings, 1 generally designates the frame of the machine which is equipped with a guide-way 2 for the vertical reciprocation of a ram 3, which is adapted to co-act with a stationary bolster plate 4 carrying the dies in operative relation to the ram 3. The plate 4 is carried by a bed-plate 5 formed integral of, or, if preferred, formed separate and secured to the frame 1 of the machine. The guard proper comprises two vertical bars 6 and 7 which are interconnected by lazy-tongs 8 which are adapted to arrange the bars 6 and 7 in spaced relation as shown in Fig. 1, or approach the 70 bars to occupy the position shown in Fig. 3.

From the foregoing it follows that the bars 6 and 7 together with the lazy-tongs 8 constitute a screen across the approach to the ram to prevent access to the space 9 between the ram 3 and the die plate 4 while in the position shown in Fig. 3, where the guard is contracted or folded, the space is accessible for the arrangement of the work and the like. The bar 7 is secured to 85 brackets 10 of a casing, generally designated by 11, by means of pins 12 so that the bar 7 is held stationary, whereas the bar 6 is adapted to execute a horizontal reciprocation in a manner hereinafter further described.

The casing 11 is formed with a chamber 13 in which a cam member 14 is adapted to reciprocate vertically. The cam is provided with an upper wide portion 15 formed with a straight edge 16 adapted to contact with the wall of the chamber 13. The cam is also provided with a cam face 17 and terminates in a reduced downwardly extending portion 18 which slides in a correspondingly shaped extension 19 of the chamber 13. The casing 11 is formed with a lateral flange 20 provided with apertures for the passage of bolts 21 whereby the casing is secured to the bolster plate 4 and is held in fixed relation with respect to the operating parts of the press.

In order to maintain the cam 14 in the casing a cover plate 22 is provided which encompasses the top and a portion of the side of the casing and is secured thereto by 5 a plurality of screws 23. The cover is equipped at the side with a threaded member 24 to which one end of a helical spring 25 is secured and the other end of said spring is fastened to a screw 26 which enters the lower reduced end 18 of the cam. 10 It is obvious that the spring 25 being secured to the stationary screw 24 and engaging the member 26 of the cam has a tendency to maintain the cam in the upper position, as shown in Fig. 5, and acts as a return spring when the cam has been displaced downwardly. A link 27 is secured to the threaded member 26 at one end and is articulated at the other end to a foot 15 lever or pedal 27', pivotally mounted in the press frame. A link 28 connects the pedal with the tripping mechanism of the machine and as these parts are well known in the art a further disclosure thereof is 20 thought to be unnecessary.

From the foregoing follows that upon depression of the pedal 27' the cam 14 is forced downwardly, overcoming the tension of the spring 25 and upon release of the treadle 27' the spring 25 acts to return the cam to the upper or inoperative position.

The casing 11 is formed with a horizontal bore 29 in which a push rod 30 is mounted for horizontal reciprocation. The rod 30 is 35 equipped at its inner end with a roller 31 which bears on the inner faces of the cam and which by the cam face 17 is ejected for a purpose presently to be described. The outer end of the rod 30 is formed with an aperture 32 and a pin 33 at a pivotal point of the lazy-tongs extends through the aperture 32 so as to couple the lazy-tongs with the push rod 30. A spring 34 is secured at 40 one end to the pin 33 and on its other end to a pin 35, laterally projecting from the casing and constituting a return spring.

From the foregoing it is obvious that upon depression of the pedal 27' the cam 14 is lowered whereby the cam edge 17, bearing 50 on the roller 31, ejects the push rod 30, causing the guard to be expanded. Upon release of the pedal the spring 25 will raise the cam and the spring 34 will cause not only the lazy-tongs to contract but 55 concomitantly will force the rod 30 into the casing in engagement with the cam. Attention is called to the fact that the expanded position of the tongs is maintained by the flat face 16 of the cam after the descent of the ram or of the pedal 27, which by the agency of the link 28 effects the 60 ascent of the ram. The horizontally reciprocating guard when expanding will push the hands of the operator out of the path 65 of the ram, if he has failed to withdraw

them in time, and access to the ram is not possible until it has been raised.

While the drawings disclose the preferred embodiment of the invention, numerous changes and alterations may be made without departing from the spirit of the invention and all changes constituting departures within the scope of the invention are included as set out in the appended claims.

I claim:

1. The combination with a press having a movable member cooperating with a stationary member, of a casing secured to said stationary member, a guard secured to the casing and unfoldable across the approach to the movable member and foldable to clear the approach to said movable member, and reciprocatory cam operated means arranged in said casing for actuating said guard.

2. The combination with a press having a movable member cooperating with a stationary member, of a casing secured to said stationary member, a guard secured to said casing unfoldable across the approach to the movable member and foldable to clear the approach to said movable member, and cam-operated means arranged in said casing for actuating said guard.

3. The combination with a press having a movable member cooperating with a stationary member, means for controlling the operation of said press, a casing secured to said stationary member, a guard secured to said casing and unfoldable across the approach to the movable member and foldable to clear the approach to said movable member, cam-operated means arranged in said casing for actuating said guard, and means connecting said cam-operated means with said press controlling means.

4. The combination with a press having a movable member cooperating with a stationary member, means for controlling the operation of said press, a casing secured to said stationary member, a guard secured to said casing and unfoldable across the approach to the movable member and foldable to clear the approach to said movable member, cam-operated means arranged in said casing for actuating said guard, and a link connecting said cam-operated means with said press controlling means.

5. A guard for presses comprising a casing adapted to be secured to the frame of a built press, parallel bars one of which is secured to said casing out of the path of the movable press member and the other is movable across the approach to said member, lazy-tongs connecting said bars, and cam-operated means arranged in said casing for actuating said movable bar.

In testimony whereof I have hereunto affixed my signature this day of October, 1921.

CHARLES HAVLISH.
